UNITED STATES PATENT OFFICE

2,473,296

MINIATURE ANIMAL TOY CAR

Jack N. O'Connor and Stella M. O'Connor,
Los Angeles, Calif.

Application November 13, 1945, Serial No. 628,126

2 Claims. (Cl. 280—8)

1

Our invention relates to improvements in what we have chosen to term a miniature animal toy car, this application being a continuation in part of the improvement set forth in our companion applications, Serial No. 592,854, filed May 9, 1945; Serial No. 602,978, filed July 3, 1945 (now abandoned); Serial No. 605,296, filed July 16, 1945; Serial No. 607,207, filed July 26, 1945 (now abandoned), and Serial No. 613,924 filed August 31, 1945 (now abandoned).

The present application relates more particularly to a combination rocker and sleigh runner attachment for a wheeled toy car or vehicle of the character set forth in our applications above identified, whereby the wheeled toy car referred to can be easily and quickly converted and used as a rocker or as a sleigh.

The primary object of our invention is the production of a wheeled vehicle or toy car of the character above referred to which can be easily and quickly converted as stated without the use of tools, for use either as a rocker or as a sleigh, whereby the usefulness of the device is extended and the amusement and satisfaction of a child is more completely gratified. Among further objects of our invention is maximum simplicity of construction and effectiveness in use.

In the accompanying drawings forming part of this specification, Fig. 1 is a perspective view of our improved miniature animal toy car showing our combined rocker and sleigh attachment applied thereto; Fig. 2 is a perspective view of the cradle rocker attachment removed from the miniature animal toy car; Fig. 3 is a side elevation on a slightly enlarged scale, of the cradle rocker with one of the sleigh runners attached to one of its rockers and showing the manner in which the cradle rocker is removably attached to the body of the miniature animal toy car; Fig. 4 is a perspective view of a detail portion of one of the sleigh runners, and Fig. 5 is a cross section on an enlarged scale, taken on the line 5—5 of Fig. 3.

As shown in the drawings, our miniature animal toy car or vehicle has a body A which is formed with a rearward seat 10, a flat circular head 11 and an interconnecting web 12. The body is normally supported by rearward and forward pairs of carrier wheels 13 and 14, the latter being vertically swiveled at 15 on the body and the swivel connection carrying the miniature figure 16 representing the head portion of an animal such as a horse. The swivel connection 15 is of ordinary construction and may be in the form of a well known king pin which is usually employed

for similar purposes. The body is intended to support a child or infant while the latter is seated upon the seat 10 with his or her legs astride of the web 12 and the feet are supported upon a tray 17, which latter is hung below the body. A suitable upstanding shield 18 is shown secured by its lower portion at 19 to the seat and by its forward portion to a bifurcated handle 20, which in turn is fastened at 21 to the figure portion 16. 5 The forward connection thus provided serves to hold the figure 16 rigidly and the forward wheels from turning by the swivel connection 15. A handle 22 which is connected to the rearward portion of the vehicle enables an operator to push, pull or guide the vehicle. The handle may be attached to any suitable portion of the vehicle and is not an essential portion of the invention as the vehicle can be guided or propelled without the use of a handle. The structure as described 10 corresponds substantially with the structure set forth in our companion applications for patents above identified, said structure representing one form of wheeled vehicle to which our improvements are applicable, it being understood that 15 the improvements hereinafter set forth are 20 equally applicable to many other types and constructions of vehicles without departing from the 25 spirit of the invention.

Our improvements provide a cradle rocker B 30 which is removably secured to the lower side of the body A of the vehicle so that the latter can be rocked by an attendant by the use of the handle 22 or by the occupant tilting the vehicle structure up and down. The cradle rocker 35 resembles a unitary skeleton frame which is formed with a pair of corresponding rocker members or treads 25 and 26, each of which has upwardly curved opposite ends. The upwardly curved portions of the pair of rockers at each end of the 40 cradle are formed with reversely curved portions 27 which extend inwardly from each end of the cradle and converge upwardly and inwardly and terminate in forward and rearward integral offset transverse supporting loops 28 and 29. The 45 rearward loop 29 is secured to the lower surface of the seat 10 by separable couplings 30 and the loop 28 is secured to the lower surface of the head 11 of the body by separable couplings such as 31. In this manner the cradle rocker is 50 secured to the vehicle and is supported to prevent lateral tilting. Suitable transverse stay arms 32 and 33 are secured between the pair of rockers or treads to assist in reinforcing the stability of the cradle frame and in maintaining the rockers 55 or treads evenly spaced apart in substantially

2

parallel relation. The cradle rocker thus provided maintains the vehicle structure with its wheels elevated sufficiently to clear the supporting surface below while the vehicle is being rocked.

Each of the rocker members 25 and 26 is provided with a pair of stops 35 which limit the rocking motion both forwardly and backwardly. Each of these stops has an outward curved end 36 for the purpose which will be hereinafter described. Consequently the cradle rocker can be easily attached to or detached from the vehicle structure when ever desired. When attached the vehicle can be used as a rocker, and operated either by the occupant or by an attendant. When not used as a rocker and the latter is detached the vehicle can be run on its carrier wheels in the ordinary manner.

In addition to a rocker attachment we also provide sled runners which can be easily secured to or removed from the pair of rocker members 25 and 26. One of these runners C is detachably secured to each of the rocker members. Each runner comprises a substantially straight tubular body 37 which is formed with up curved opposite end portions 38. These end portions are reversed and curved inwardly and are cupped at or near their extremities as shown in Fig. 4 to form spring clips 39. By curving the end members 36 of the end stops lengthwise and by shaping the clips 39 to correspond as shown the runners are adapted to interlock under spring pressure on the rockers. Also the clips thus provided on the opposite ends of each runner are adapted to be tightly engaged over the curved end members 36 of the stops to assist in holding the runners on the rockers and to permit detaching the runners when ever desired. As shown in Fig. 5 the body portion 40 of each rocker is circular in cross section and the body portion of each runner is cut away and thus channeled downwardly and longitudinally at 41 for a suitable distance between its ends to receive and engage the lower tread surface of each rocker member and in cooperation with the clips 39 automatically and detachably hold the runner securely on the rocker tread. When thus held on the pair of rocker treads of the rocker cradle the runners enable the vehicle to be additionally used as a sleigh. By detaching the runners the vehicle can be used as a rocker and by detaching the cradle rocker the vehicle can be used as a wheeled carrier. The detaching or attaching operation in relation to the vehicle and cradle rocker, it will be noted, does not require the use of tools.

In accordance with the patent statutes, we have described the principles of operation of our invention together with the apparatus which we now consider to represent the best embodiment thereof, but we desire to have it understood that the construction shown is only illustrative and that

the invention can be carried out by other means and applied to uses other than those above set forth within the spirit of the invention and within the scope of the following claims.

5 We claim:

1. In a child's vehicle having a body, a self contained rocker element having a pair of unitary rocker treads, said treads being formed with upward reversely curved and transversely converging supporting loops at their opposite end portions, attaching means separably coupling the upper portions of said loops to the lower side of said body, stops on the lower side of the opposite ends of each tread for limiting rocking motion, and a sled runner detachably secured on the lower side of each of said treads, said runner having a tubular body formed with upward inturned end portions, said body portion being grooved longitudinally on its upper side and adapted to admit and laterally engage the lower body portion of a companion tread, and said inturned end portions being cupped and engaging under spring tension over said stops to assist in holding the runner longitudinally of the tread.
2. In a child's vehicle having a body, a self contained rocker element having a pair of unitary rocker treads, said treads being formed with upward reversely curved and transversely converging supporting loops at their opposite end portions, attaching means separably coupling the upper portions of said loops to the lower side of said body, stops on the lower side of the opposite ends of each tread for limiting rocking motion, and a sled runner detachably secured on the lower side of each of said treads, said runner having a tubular body formed with upward inturned end portions, said body portion being grooved longitudinally on its upper side and adapted to admit and laterally engage the lower body portion of a companion tread, and said inturned end portions being cupped and engaging under spring tension over said stops to assist in holding the runner longitudinally of the tread.
3. In a child's vehicle having a body, a self contained rocker element having a pair of unitary rocker treads, said treads being formed with upward reversely curved and transversely converging supporting loops at their opposite end portions, attaching means separably coupling the upper portions of said loops to the lower side of said body, stops on the lower side of the opposite ends of each tread for limiting rocking motion, and a sled runner detachably secured on the lower side of each of said treads, said runner having a tubular body formed with upward inturned end portions, said body portion being grooved longitudinally on its upper side and adapted to admit and laterally engage the lower body portion of a companion tread, and said inturned end portions having means for clasping said stops to assist in holding the runner longitudinally on the tread.
